UNITED STATES PATENT OFFICE.

THOMAS C. JOHNSON, OF NEW HAVEN, AND FRANK F. BURTON, OF EAST HAVEN,
CONNECTICUT, ASSIGNORS TO WINCHESTER REPEATING ARMS CO., OF NEW
HAVEN, CONNECTICUT, A CORPORATION.

DEVICE FOR LOADING BOX-MAGAZINES.

1,295,038.

Specification of Letters Patent. Patented Feb. 18, 1919.

Application filed November 10, 1917. Serial No. 201,275.

To all whom it may concern:

Be it known that we, THOMAS C. JOHNSON and FRANK F. BURTON, citizens of the United States, residing, respectively, at New Haven and East Haven, in the county of New Haven and State of Connecticut, have invented a new and useful Improvement in Devices for Loading Box-Magazines; and we do hereby declare the following, when taken in connection with the accompanying drawings and the characters of reference marked thereon, to be a full, clear, and exact description of the same, and which said drawings constitute part of this application, and represent, in—

Fig. 1 a view in front elevation of our improved device for loading box-magazines.

Fig. 2 a view thereof in side elevation with the body part of a paper carton filled with cartridges shown as held in the hand preparatory to feeding a column of cartridges from it directly into the device.

Fig. 3 a view of the device in horizontal section on the line 3—3 of Fig. 2.

Fig. 4 an enlarged view in horizontal section on the line 4—4 of Fig. 2, showing the chambered upright and the cartridge-guide.

Fig. 5 a view of the device in vertical section, showing the pivotal loading-head engaged with the uppermost cartridge of a column of fed cartridges preparatory to charging the same into a box-magazine.

Fig. 6 a corresponding view showing the cartridges after they have been charged into the box-magazine.

Fig. 7 a detached plan view of the pivotal loading-head and the plunger to which it is pivoted.

Fig. 8 a detached plan view of the plunger.

Our invention relates to an improved device for loading cartridges into box-magazines for subsequent introduction, as loaded magazines, into machine guns or shoulder arms, the object being to provide a simple, durable, reliable and rapidly operated portable device of the character described, the said device being particularly adapted to loading tapering cartridges directly from paper cartons, though not so limited, since it is also available for loading cartridges fed by hand into the device.

With these ends in view, our invention consists in a cartridge-loading device hav-

ing a frame provided with a cartridge-guideway, a cartridge-loading instrumentality co-acting with the said guideway, and box-magazine positioning and supporting means located at the delivery end of the said guideway.

Our invention further consists in a cartridge-loading device having a pivotal loading instrumentality, and certain other details of construction and combinations of parts as will be hereinafter described and pointed out in the claims.

In carrying out our invention, as herein shown, we employ a leaf-like pivotal cartridge-loading instrumentality or head 5 having at its lower end a straight loading-face 6, substantially as long as the body-portion of a tapering cartridge 7. At its upper end the said head is provided with a handle 8 located substantially above an operating-pin 9 extending transversely through the lower portion of the head so as to project on opposite sides thereof. The upper end of the said head is also furnished with an arm 10 entered into a slot 11 in the upper end of a plunger 12, and secured in place in the said slot by means of a pivot 13 on which the head rocks in the vertical plane, whereby the device is adapted to load tapering cartridges, as will be hereinafter explained. The said plunger 12 is mounted for vertical reciprocation in the chamber 14 of a tubular upright 15 the lower end of which is secured to a base-plate or pedestal 16 by screws 17 only one of which is shown, the upper end of the upright being closed by a cap 18 secured to it by screws 19, only one of which is shown. The front of the upright is formed with a flattened face 20 centrally intersected by a vertical slot 21 enough wider than the head 5 to permit the same, and the arm 10 thereof, to move up and down in it, the plunger 12 being held against rotation, and the head against lateral displacement, by the engagement of the sides of the arm 10 with the walls of the said slot. 95

Two parallel flange-like cartridge-guides 22 applied to the upright, have corresponding inclined outer edges 23 for coaction with the respective ends of the operating-pin 9, the said guides being furnished with fastening-flanges 24 receiving screws 25 by which the guides are secured in place on the opposite sides of the lower end of the slot 11. 105

The opposing inner faces of the guides 22 are formed (Fig. 4) with vertically arranged ribs 26 which enter the cannelures or grooves 27 in the heads of the cartridges, in case they are rimless cartridges like the cartridges 7, or engage with the under faces of the rims of rim-cartridges of the well known form. As will be seen by Fig. 4, the ribs 26 are in spaced relation to the face 20 aforesaid, so as to provide, as it were, a cartridge-guideway 29 for the head-ends of the cartridges. As shown, the inner faces of the guides 22 are also formed with shallow clearance grooves 30 to reduce friction and so permit the cartridges to feed freely. The edges 23 of the cartridge-guides 22 are properly inclined with respect to the inclination of the axes of the cartridges 7, as piled, so as to co-act with the respective projecting ends of the operating-pin 9, as the loading head 5 is forced directly downward by its handle 8, to cause the loading-face 6 of the said head 5 to maintain itself in engagement with the uppermost cartridge, the inclination of which grows gradually less as the column of cartridges descends into the box-magazine 31, whereby the successive cartridges are entered into the mouth of the box-magazine in the same relative position thereto. As herein shown, the box-magazine is furnished with a follower 32 and follower spring 33. Conversely, the cartridges, whatever their position in the magazine, are fed out of the same so that the uppermost cartridge therein, that is, the cartridge at the mouth thereof, always takes the same feeding position. In other words, the respective cartridges are always fed into and out of the magazine in a predetermined position with respect to the mouth thereof, whatever that position may be.

For the purpose of temporarily positioning and supporting the box-magazines at the lower or delivery end of the cartridge-guideway 29, we employ, as shown, a horizontal, loop-like upper magazine-support 34 secured to the tubular upright 16 by screws 35, the said support being cut away on its right hand side as at 36 to facilitate the entrance into it of the upper ends of the box-magazines, the lower ends of which are rested upon a lower box-magazine support consisting, as shown, of a wedge-like block 37 secured to the base 16 by screws 38, and having its upper face inclined from front to rear to correspond to the beveled lower ends of box-magazines of the type of the box-magazine 31, whereby the magazines must be properly presented in order to be set up in the device. The upper left hand corner of the block is provided with a stop-rib 39 which prevents the lower end of the magazine from being pushed too far from right to left in setting up the magazine in the device. As thus constructed it is im-

possible to position a box-magazine in the device in any position except the right position.

A helical spring 40 located within the plunger 12 and resting at its lower end upon the base-plate 16, exerts a constant effort to lift the plunger so as to normally support the loading-head 5 in the position in which it is shown in Figs. 1 and 2.

In the use of our improved device, the cover having been removed from a paper carton filled with cartridges, assuming for the sake of description that the cartridges to be loaded are supplied to the operator in paper cartons, rather than in bulk, or in some other form of package than a carton, the box-part 41 of the carton while grasped by the hand of the operator, is used to bring the projecting heads of all of the cartridges in the carton, into simultaneous engagement with the face 20 of the tubular upright 15 at a point on the said face, between the upper ends of the cartridge-guides 22 and the loading-face 6 of the loading-head 5. The carton is then slid downward for the entrance of the lowermost cartridge of one of the contained columns between the upper ends of the cartridge-guides 22, and therefore into the upper or receiving end of the cartridge-guideway 29. The carton is, by a sweeping, movement of the hand, now drawn downward, whereby the cartridges of the whole column are caught by their heads, as it were, in the said cartridge-guideway 29 in which they are retained by the ribs 26 of the guides 22. The box-part 41 of the carton is then drawn laterally away from the upright 15, thus stripping the cartridges out of the carton. The column of cartridges will now rest upon the magazine-follower 32. Assuming that an empty box-magazine has been positioned in the device, the handle 8 is now grasped, and the loading-head 5 forced directly downward against the tension of the spring 40, whereby the loading-face of the head 5 will engage with the body of the uppermost cartridge, as shown in Fig. 5, at which time the projecting ends of the pin 9 will be engaged with the upper portions of the inclined edges 23 of the cartridge-guides 22. As the column of cartridges is forced downward, the inclined edges 23 acting through the ends of the pin 9, will progressively swing the loading-head 5 outward so as to keep its loading-face 6 in engagement with the uppermost cartridge by compensating, as it were, for the constant change in the pitch or inclination thereof as the column descends into the box-magazine, the pitch being reduced by the taper of one cartridge as each cartridge successively enters the magazine. To effect this result, the said inclined edges 23 of the guides 22 have to be properly inclined to cover the extreme variation in the pitch of an entire

column. When the column rests upon the follower 32 as shown in Fig. 5, all of the cartridges, except the lowermost cartridge, will have their bullet ends inclined downward with the lowermost cartridge in its delivery position. On the other hand, after the column of cartridges has been introduced into the magazine, the uppermost cartridge occupies the correct delivery position there-
 5 in, while all of the cartridges below it have their bullet ends correspondingly inclined upward as indicated in Fig. 5, the cartridges being exactly reversed in the matter of inclination. The cartridges occupy these in-
 10 clined positions because their body portions are slightly tapering rather than cylindrical. For this reason they are loaded in the manner described to prevent them from cocking or tilting as they enter the magazine. On
 15 releasing the downward pressure upon the handle 8, the plunger spring 40 asserts itself to lift the loading-head 5 to the top of the upright 15 as shown in Fig. 1, for loading another box-magazine. The remaining col-
 20 umn of cartridges in the carton will now be loaded in the same manner into the same magazine, or into another magazine, as the case may be, supposing each carton to have two columns of cartridges, which is the
 25 usual practice.

We claim:

1. In a device for loading box-magazines for firearms, the combination with a frame having a cartridge-guideway, of a cartridge-
 30 loading instrumentality adapted to traverse the said guideway and arranged so that the inclination of its loading-face will be pro-
 35 gressively changed to compensate for the gradual changing of the inclination of the column of cartridges in the guideway, due to the taper of the cartridges, and means for positioning and supporting a box-magazine at the cartridge delivery end of the said guideway.

45 2. In a device for loading box-magazines for firearms, the combination with a pivotal cartridge-loading instrumentality, of means for progressively swinging the said instru-
 50 mentality during the loading of the cartridges into a box-magazine, whereby their change in inclination or pitch due to their taper, is compensated for.

55 3. In a device for loading box-magazines for firearms, the combination with means for positioning and supporting a box-magazine, of cartridge-guides located above the said means, a pivotal cartridge-loading head co-
 60 acting with the said guides and having a loading-face, and means for swinging the said head upon its pivot so as to pro-
 65 gressively change the inclination of its loading-face to insure the introduction of the successive cartridges into the mouth of the box-
 70 magazine at the same angle.

75 4. In a device for loading tapering car-

tridges into box-magazines for firearms, the combination with a pivotal loading-head, of means for progressively swinging the said head during the loading of the cartridges into a box-magazine, whereby their change in inclination or pitch due to their taper, is compensated for.

5. In a device for loading cartridges into box-magazines directly from cartons, the combination with a pivotal loading-head 75 having a loading-face, of cartridge-guides having their edges inclined to co-act with the said head to rock the same on its pivot as it descends for insuring the entrance of the successive cartridges of the column into 80 the mouth of a box-magazine at the same angle.

6. In a device for loading box-magazines for firearms, the combination with a cham-
 85 bered upright having its front face flattened and slotted, of a spring-actuated plunger located in the said upright, a cartridge loading-head pivoted to the said plunger and traveling up and down in the said slot, magazine-supporting means, cartridge-
 90 guides carried by the said upright and interposed between the said head and the said magazine-supporting means, and means for rocking the said head upon its pivot so as to cause the successive cartridges to enter 95 the mouth of the magazine at the same inclination.

7. In a device for loading box-magazines for firearms, the combination with a cham-
 100 bered upright, of a base therefor, a lower box-magazine support upstanding from the said base, a loop-like upper magazine-sup-
 105 port applied to the upright at a point directly above the said lower support, a spring-actuated plunger located in the chamber of the said upright, a loading-head 110 pivotally connected with the upper end of the plunger, and cartridge-guides carried by the said upright and adapted to receive the said head which descends between them and to rock the same upon its pivot during its descent.

8. In a device for loading box-magazines for firearms from cartons, the combination with a pivotal loading-head having a load-
 115 ing-face, provided with an operating-handle and carrying an operating-pin located sub-
 120 stantially below the said handle, of cartridge-guides having their edges inclined for co-operation with the said pin for rock-
 125 ing the said head during its descent between the said guides, and means for positioning and supporting a box-magazine below the said guides during the loading operation.

9. In a device for loading box-magazines for firearms, the combination with means for forcing a column of cartridges into the mouth of a box-magazine, of a loop-like magazine support cut away on one side, 130

whereby the introduction of the upper end of the magazine is facilitated, and whereby its opposite side forms a stop for positioning the magazine for the reception of the 5 cartridge.

10. In a device for loading tapering cartridges into box-magazines for firearms, the combination with a chambered upright having its forward face flattened and centrally intersected by a vertical slot, of a spring-actuated plunger located in the upright, a loading-head pivotally connected with the upper end of the said plunger, and provided with a handle and with an 15 operating-pin, cartridge-guides located below the said head and having their edges inclined for co-action with the said pin to rock the said head upon its pivot to compensate for the tapering character of the 20 cartridges, and means for temporarily positioning and supporting a box-magazine in alinement with the lower ends of the said guides.

25. In a device for loading box-magazines for firearms, the combination with loading instrumentalities, of a loop-like upper magazine-support cut away on one side, and a wedge-like lower magazine-support formed with a stop flange along its side opposite 30 from the side on which the said loop-like support is cut away.

12. In a device for loading box-magazines for firearms, the combination with an upright, of cartridge-guides carried thereby

and having inclined edges, means for positioning and supporting a box-magazine below the said guides, a spring-actuated plunger located in the upright, and a loading-head pivotally connected with the said plunger and provided with a loading-face, 35 a handle, and an operating-pin, the said pin being located substantially in line below the said handle, pressure upon which thus maintains the pin in engagement with the inclined edges of the cartridge-guides, 40 whereby the pressure exerted through the handle to push the column of cartridges downward through the cartridge-guides into the box-magazine maintains the pin in engagement with the said inclined edges. 45

13. In a device for loading box-magazines for firearms, the combination with a frame having a cartridge-guideway organized with it, of a cartridge-loading instrumentality adapted to enter the receiving-end of the said guideway, and means for supporting and positioning a box-magazine with respect to the said guideway, and a guard for preventing the improper insertion of the 55 magazine into the device. 60

In testimony whereof, we have signed this specification in the presence of two subscribing witnesses.
